UNITED STATES PATENT OFFICE.

BENJAMIN A. MITCHELL, OF GARFIELD, UTAH.

SCREENING MACHINE AND SCREEN CLOTH THEREFOR.

Application filed September 30, 1920. Serial No. 413,843.

To all whom it may concern:

Be it known that I, BENJAMIN A. MITCHELL, a citizen of the United States, residing at Garfield, in the State of Utah, have invented certain new and useful Improvements in Screening Machines and Screen Cloth Therefor, of which the following is a specification.

This invention relates to improvements in screen cloth for use in screening machines and to improvements in such machines for screening finely divided or crushed materials.

The principal object of the invention is to provide an improved screen cloth having relatively large or heavy wires interwoven with the comparatively fine wires which compose the body portion of the screen. Another object of the invention is to provide a woven wire screen cloth reinforced with heavy wires, in which the dimensions of the meshes of the cloth, transversely to the heavy wires, are substantially uniform throughout the screen. Still another object is to provide a woven wire screen cloth having relatively large wires of approximately elliptical or oblong cross section interwoven with the fine wires of the screen. Other objects relate to various features of construction and arrangement such as will be more fully pointed out hereinafter.

The nature of the invention will be understood from the following specification taken in connection with the accompanying drawings, in which certain embodiments are illustrated.

In the drawings—

Fig. 1 shows a top plan view of the improved screen cloth;

Fig. 2 shows a sectional view transversely to the heavy wires on the line 2—2 of Fig. 1;

Fig. 3 shows a longitudinal sectional view on the line 3—3 of Fig. 4, illustrating one method of connecting the screen cloth to the screening machine;

Fig. 4 shows a top plan view of a screening machine with the improved screen cloth embodied therein;

Fig. 5 is a perspective view of the machine illustrated in Fig. 4 looking toward the under side thereof;

Fig. 6 shows a side elevation of the screening machine with a feeding device shown in vertical section;

Fig. 7 shows an enlarged vertical section through the screen cloth transversely to the

heavy wires thereof, showing the character of the vibrations which may be set up in the screen cloth;

The form of screen cloth illustrated particularly in Figs. 1 and 2 comprises a plurality of longitudinal weft wires 15 which are interwoven with a plurality of transversely extending warp wires 16. The wires 15 and 16 are comparatively small in cross section and the wires 15 have substituted therefor, at predetermined intervals, the comparatively large weft wires 17 which are preferably oblong or approximately elliptical in cross section, as illustrated in Fig. 2. The fine wires 15 and 16 are spaced equal distances apart to form meshes 18, which are substantially rectangular and it has been found that, by employing heavy wires 17 of oblong cross section, it is possible to maintain the meshes 18 uniform in size throughout the width of the screen cloth. If the heavy wires 17 were circular in cross section and of a diameter equal to the shorter dimensions of these wires, as illustrated in Fig. 2, it will be apparent that the meshes 18^a on each side of each heavy wire would have dimensions transversely to the heavy wires greater than the corresponding meshes formed by the interwoven fine wires. The use of a heavy wire having an oblong cross section overcomes this difficulty, due to the fact that the projecting lateral edges of the heavy wires partially fill the meshes so that the openings 18^a adjacent the heavy wires can be maintained the same in size as any of the other meshes formed by the fine wires alone. The screen cloth thus formed is particularly adapted for use in screening meshes for screening or separating crushed ore, sand, gravel, or other similar materials which are caused to pass over the screen cloth, preferably while it is being vibrated. The heavy wires give an increased stiffness to the screen cloth and are adapted to increase the efficiency of the vibrations therein and, while at the same time, the provision of a uniform size of mesh makes it possible to maintain a uniform fineness of the screened material.

There is illustrated in Figs. 4, 5 and 6 an application to a screening machine of screen cloth made in accordance with this invention. The machine here shown comprises a frame 20 having a centrally located cross frame member 21 united at its ends with upwardly extending arms 22. These mem-

bers 22 are flared outwardly at their upper ends and terminate in the end frames 23 of angular cross section having upwardly extending flanges 23^a and inwardly directed flanges 23^b. The screen cloth shown at 25 has relatively large or heavy wires 25^a interwoven therein extending longitudinally thereof, and is mounted between the end frame members 23 the screen being secured thereto by means of pairs of clamping bars 26. These clamping bars are placed on opposite sides of the screen cloth and are secured together by bolts 27 so that the bars 26 are caused to grip firmly the heavy wires 25^a of the screen cloth. The lower bar 26 of each pair has a number of longitudinally extending bolts 28 welded thereon, or otherwise secured thereto, and these bolts are adapted to engage the notches 29 which are formed in the end frame members 23^a. The threaded extremities of the bolts 28 are engaged by nuts 30 so that a tension can be created in the screen cloth longitudinally of the heavy wires 25^a.

25 The screen frame 20, as illustrated in Fig. 6, is stationarily supported in screening position with the screen cloth preferably in an inclined position. The upper extremities of the end frame members 23 are provided with longitudinally extending pins 32 adapted to engage the brackets 33 carried by the vertical wall 34. On their lower extremities, the end frame members 23 are provided with cylindrical projections or bosses 35 which are threadedly engaged by vertically extending adjusting members 36. These adjusting members engage plates 37 secured to the upper edge of a vertical supporting wall 38 and, by regulating the members 36, it is possible to vary the inclination of the screen frame and the corresponding inclinations of the screen cloth carried thereby. The adjusting members 36 are secured in adjusted position by means of lock nuts 39. The material to be screened is delivered from a hopper 40 from which it passes onto a rotary drum conveyor 41 and is distributed thereby from an auxiliary hopper 42 onto the upper edge of the screen cloth, as illustrated at 43.

50 The material to be screened passes downwardly by gravity over the inclined screen cloth, and is subjected to the action of high frequency vibrations set up in the screen cloth by means of the vibrator 45, which preferably is of the type disclosed in my copending application, Serial No. 275,321, utilizing the principle of rotating moments to produce a high frequency harmonic motion or vibration in planes transverse to the axis of symmetry.

55 The vibrator 45 is shown as mounted at a point substantially midway of the longitudinal frame member 21, the vibrator being held in position by means of the strap 65 which extends around its casing and is pro-

vided with threaded extremities 66 adapted to engage the brackets 67 secured to opposite sides of the frame member. The ends of the threaded bars 67 are engaged by nuts 68 which may be adjusted to regulate the pressure with which the vibrator is held in position on the frame. The mounting for the vibrator 45 is preferably a single point support under its centre of gravity which in the instance shown is in the central part thereof. This mounting would preferably comprise a supporting collar having a spherical surface on the frame 20 which engages with a co-acting member on the vibrator casing to provide a pivotal support which would afford substantially universal movement though limited of the casing when executing vibration. Compressed air may be used to cool this apparatus. To this end it is shown as provided with an aperture 72 where air may be introduced and circulated through the frame 20 and thence up into the vibrator casing.

60 The vibrations executed by the projecting ends of the vibrator 45 are imparted to the screen cloth by means of transmitting plates 75 which are of the form illustrated particularly in Fig. 5. These plates are provided with apertures which are adapted to be closely fitted by the tapered extremities 76 of the vibrator casing and the plates are held in position on the vibrator casing by means of keys 77 extending transversely through apertures formed in the projecting end flanges 78. The upper edges of the plates 75 have strips 80 of wood, or the like, secured thereto and adapted to engage the under side of the screen cloth 25. The upper edge of each plate 75 is preferably somewhat angular in contour, as shown in Fig. 5, and the strips 80 are arranged at corresponding angles to conform to the inclination of the screen cloth which is preferably formed in two sections having different inclinations to the horizontal so that the finely divided materials passing downwardly over the screen cloth are retarded as the lower edge of the screen is approached. The transmitting plates 75, extending upwardly from the vibrator, are adapted to transmit the circular vibrations from the casing of the vibrator 45 to the screen cloth so that high frequency vibrations are set up in the screen cloth in planes parallel to the paths of travel of the materials being screened and transversely to the direction in which the heavy wires 25^a extend. In practice, the vibrator is preferably located in such a direction that each particle of the screen cloth will travel toward the upper edge of the screen when in the upper part of its path of vibration. The vibrator 45 is preferably so constructed that, in operation the ends of its casing execute vibrations which are substantially out of phase by 180 degrees, so that it behaves sub-

stantially like a double conical pendulum vibrating. The vibrations are not necessarily circles, but they are harmonic vibrations having closed orbits, and a constantly changing direction of motion. With the arrangement described, each particle of the screen cloth is caused to travel in a minute closed path, as illustrated by the arrows 88 in Fig. 7 of the drawings, where the longitudinal heavy wires 25^a have a plurality of longitudinal fine wires 25^b arranged between them. Both the heavy wires 25^a and the fine wires 25^b are interwoven with the transverse fine wires 25^c.

15 Instead of mounting the screen cloth in a frame, as shown in Figs. 4 and 5, the vibrator 90 may be secured to a fixed frame member 91 by means of a strap 92, as shown in Fig. 12, with the free ends of the vibrator 20 projecting on opposite sides of the frame and carrying the transmitting plates 93 secured thereto in the manner heretofore described. The transmitting plates 93 are engaged by the adjusting bolts 94 which are 25 secured to clamping members 95 attached to the screen cloth 96. The screen cloth is thus supported by the transmitting plates 93, and the bolts 94 may be adjusted to create a tension in the screen cloth if a tension is 30 desired.

Although I have shown and described certain forms of the invention for purposes of illustration, it will be understood that it may be constructed in various ways without departing from the scope of the appended 35 claims.

I claim:

1. A wire screen cloth adapted to be vibrated in screening machines comprising a 40 warp and weft of relatively fine wires, said fine wires being replaced at predetermined intervals with relatively heavy wires having an oblong cross-section whereby a reinforced screen cloth having substantially uniform 45 mesh throughout is provided.

2. A wire screen cloth adapted to be vibrated in screening machines comprising a warp and weft of relatively fine wires, said screen adapted to be supported in a state of 50 tension and having the fine wires extending in the direction of tension replaced at predetermined intervals with relatively heavy wires having an oblong cross-section.

3. A wire screen cloth adapted to be vibrated in screening machines comprising a warp and weft of relatively fine wires, said screen adapted to be supported from two edges longitudinally displaced and having the fine wires extending longitudinally 55 replaced at predetermined intervals with relatively heavy wires having an oblong cross-section.

4. A wire screen cloth adapted to be vibrated in screening machines comprising a 60 warp and weft of relatively fine wires, said

screen cloth having relatively large wires interwoven therein at predetermined intervals and formed with a cross-section yielding substantially uniform mesh in directions transverse thereto.

5. A wire screen cloth adapted to be vibrated in screening machines comprising a warp and weft of relatively fine wires, said screen cloth having relatively large wires interwoven therein at predetermined intervals formed with approximately elliptical cross-sections.

6. A wire screen cloth adapted to be vibrated in screening machines comprising a warp and weft of relatively fine wires, said screen cloth having relatively large wires interwoven therein at predetermined intervals formed with approximately elliptical cross-section having its greater dimension 80 lying in the plane of the screen cloth.

7. A wire screen cloth adapted to be vibrated in screening machines comprising a warp and weft of relatively fine wires, said screen adapted to be supported in a state of tension having the fine wire extending in the direction of tension replaced at predetermined intervals with relatively heavy wires formed with approximately elliptical cross-sections and arranged to have their greater dimension lie in the plane of the screen 95 cloth.

8. In a screening machine, the combination with a vibrator, of a screen cloth reinforced at intervals with interwoven relatively heavy wires adapted to sustain directly the stress of the received vibrations, said reinforcing wires having a cross-section altered whereby to produce a cloth of substantially uniform mesh, and means for imparting motion from said vibrator to said 100 screen.

9. In a screening machine, the combination with a vibrator, of a screen cloth reinforced at intervals with interwoven relatively heavy wires adapted to sustain directly the stress of the received vibrations, said reinforcing wires having an approximately elliptical cross-section, means for retaining said screen under tension, and means for imparting motion from said vibrator to 105 said screen.

10. In a screening machine, the combination with a vibrator, of a screen cloth reinforced at intervals with interwoven relatively heavy wires adapted to sustain directly the stress of the received vibrations, said reinforcing wires having an approximately elliptical cross-section, means for stationarily supporting said screen, means for retaining said screen under tension, and 110 means for imparting motion from said vibrator to said screen.

In testimony whereof, I have subscribed my name.

BENJAMIN A. MITCHELL.
